DESIGN FOR A GLOVE

Kay Fuchs, New York, N. Y.

Application March 23, 1940, Serial No. 91,196

Term of patent 3½ years

To all whom it may concern:

Be it known that I, Kay Fuchs, a citizen of the United States of America, residing in New York city, in the Borough of Manhattan, county and State of New York, have invented a new, original, and ornamental Design for a Glove, of which the following is a specification, reference being had to the accompanying drawing, forming part thereof, wherein,

The characteristic feature of my design resides in the ornamental tabs attached to the upper end of the glove, as shown.

I claim:

The ornamental design for a glove, substantially as shown and described.

KAY FUCHS.
